UNITED STATES PATENT OFFICE

150,400

DESIGN FOR PLAY YARD EQUIPMENT

Ralph T. Bowden and George B. Roberts,
Brunswick, Ga.

Application February 13, 1947, Serial No. 136,880

Term of patent 3½ years

(Cl. D34—5)

To all whom it may concern:

Be it known that We, Ralph T. Bowden, and George B. Roberts, citizens of the United States, residing at Brunswick, in the county of Glynn and State of Georgia, have invented a new, original, and ornamental Design for Play Yard Equipment, of which the following is a specification, reference being had to the accompanying drawing, forming part thereof.

The drawing is a perspective view of the play yard equipment showing our new design.

We claim:

The ornamental design for play yard equipment, as shown.

RALPH T. BOWDEN. —
GEORGE B. ROBERTS.
